AIRCRAFT INSTRUMENT

William P. Lear, Pacific Palisades, and Edward F. O'Brien, Santa Monica, Calif., assignors to Lear, Incorporated

Filed Aug. 20, 1958, Ser. No. 52,303

Term of patent 14 years

(Cl. D52—6)

Fig. 1

Figure 1 is a front elevational view of an aircraft instrument showing our new design;

Figure 2 is a side view thereof; and

Figure 3 is a vertical sectional view thereof taken substantially along the line 3—3 of Figure 1.

The essential features of the design reside in the full line portions.

We claim:

The ornamental design for an aircraft instrument, substantially as shown and described.
